UNITED STATES PATENT OFFICE.

FREDERIC AUMONIER, OF LONDON, ENGLAND.

DESIGN FOR WALL AND CEILING PAPER.

SPECIFICATION forming part of Design No. 22,805, dated September 26, 1893.

Application filed August 28, 1893. Serial No. 484,266. Term of patent 3½ years. Patented in England March 3, 1893, No. 208,523.

To all whom it may concern:

Be it known that I, FREDERIC AUMONIER, (trading as WM. WOOLLAMS & Co.), a subject of the Queen of Great Britain, and a resident 5 of 110 High Street, near Manchester Square, London, England, have invented a new and useful Design for Wall and Ceiling Paper, (patented in Great Britain March, 3, 1893, No. 208,523,) of which the following is a specification.

This design for wall and ceiling paper is shown on the accompanying drawing and consists of three distinct devices. One or center device consists of a double lined circle containing a Tudor rose around which are two circles and then a ring of semispheres connected by lines with ornamentations between. Around the outer circle are arranged segments of circles having their ends scrolled inward 15 and connected to the outer circle by lines, ornamentations being placed in the spaces.

The second device consists of a Tudor rose arranged in a square having ornaments on the sides and corners, this being in a square,

around which are arranged ornamental scrollings, the whole being inside a kind of square having two opposite sides domed and the other two opposite sides recessed with the segments of the circles arranged to a point.

The third device consists of a Tudor rose, 30 around which are ornamental scroll work arranged within a square, on each side of which are domed oblongs, these being filled with a scrollwork.

The second and third mentioned devices 35 are arranged alternately to form a square around the first mentioned device. The spaces between the devices are ornamented with scroll work.

I claim

The design for wall and ceiling paper substantially as shown and described.

FREDERIC AUMONIER.
